COMBINED PHONOGRAPH RECORD AND SUP-
PORT FOR FIGURE TOY OR THE LIKE

Frank J. Kughta, Redondo Beach, and Richard L. May,
Manhattan Beach, Calif., assignors to Mattel, Inc.,
Hawthorne, Calif.

Filed Dec. 9, 1970, Ser. No. 26,382

Term of patent 14 years

Int. Cl. D21—01

U.S. Cl. D34—4

FIG. 1

FIG. 4

FIG. 2

FIG. 5

FIG. 3

FIG. 6

FIG. 7

FIG. 8

FIG. 1 is a perspective view taken from the top of a combined phonograph record and support for figure toy or the like embodying our design;

FIG. 2 is a top view of same;
FIG. 3 is a front view of same;
FIG. 4 is a bottom view thereof;
FIG. 5 is a left side view thereof;
FIG. 6 is a right side view thereof;
FIG. 7 is a rear view of same; and
FIG. 8 is a view similar to that of FIG. 2 but here depicting the instant design with recording grooves.

We claim:

The ornamental design for a combined phonograph record and support for figure toy or the like, as shown and described.
